UNITED STATES PATENT OFFICE.

EDWARD L. GAYLORD, OF BRIDGEPORT, CONNECTICUT.

PIPE-BOWL.

No. 826,098.

Specification of Letters Patent.

Patented July 17, 1906.

Application filed July 6, 1905. Serial No. 268,457.

To all whom it may concern:

Be it known that I, EDWARD L. GAYLORD, a citizen of the United States, residing at Bridgeport, in the county of Fairfield and State of Connecticut, have invented certain new and useful Improvements in Pipe-Bowls; and I do hereby declare the following to be a full, clear, and exact description of the invention, such as will enable others skilled in the art to which it appertains to make and use the same.

My invention relates to pipe-bowls; and it consists in the details of construction herein-after particularly described, and then specifically pointed out in the concluding claims.

In the accompanying drawings, which form a part of this application, Figure 1 is a side elevation of my improved bowl; Fig. 2, a sectional elevation thereof; Fig. 3, a detail elevation of the meerschaum bowl with the threaded metallic band in position around the base thereof; Fig. 4, a detail sectional elevation of the amber-body portion of my improved bowl, and Fig. 5 a detail elevation showing the meerschaum bowl and the threaded band therefor in detached condition.

Similar numbers of reference denote like parts in the several figures of the drawings.

Heretofore it has been common to provide a pipe-bowl having an amber body and a meerschaum tobacco-bowl, but a female thread has been cut directly into the body of the amber itself, while a male thread has been cut around the base of the meerschaum bowl. It is very well known that amber is a very fragile substance, and it is not only true that threads cut directly into amber become easily mutilated, but all kinds of amber will not withstand a threading operation.

My improvement contemplates the protection of the engaging surfaces between the amber body and the meerschaum bowl by means of metallic portions and will be best understood from the following description:

1 is a meerschaum tobacco-bowl for a pipe having a reduced lower end 2, which has perforations 3 in the bottom leading to the interior of the bowl.

4 is a threaded metal collar secured around the reduced end 2 in any suitable manner, but in the present instance by depressing the stock of the collar into the meerschaum itself, as shown at 5.

6 is the amber pipe-bowl, provided with the usual socket 7 for the reception of the pipe-

stem, a small duct 8 leading from the socket to the interior of the body 6. Around the outside of the top of the body 6 is a metal band 9, which serves to reinforce or strengthen this body, while the inside of this body 6 at the top portion thereof is lined with a metallic threaded collar 10.

Both the outside collar 9 and the inside collar 10, or either of them, may be secured in position in the manner shown and described in Letters Patent No. 760,192, issued to me May 17, 1904; but I do not wish to be limited to any particularly manner of securing these collars in position, since they can in many instances be held in place by utilizing the relative degrees of expansion of the metal and amber.

Having thus described my invention, what I claim as new, and desire to secure by Letters Patent, is—

1. In combination with the body, and a bowl having a reduced lower end, a pair of metallic collars each consisting in its entirety of a ring-like structure, one of said collars being considerably wider than the other, the smaller of said collars being interiorly threaded and being set in the body to lie flush with the interior thereof, the larger of the collars being exteriorly threaded at its upper portion and being received about said reduced end of the bowl, the unthreaded portion of the larger collar being formed with a series of spaced depressed portions which extend into the material of the bowl.

2. In combination with the body having a cut-out portion on its interior adjacent the top thereof, a threaded metallic collar seated in said cut-out portion and disposed flush with the interior of the body and having its top edge disposed flush with the top edge of said body, a bowl having a reduced lower end, a metallic collar of considerably greater width than said first-named collar surrounding the reduced end and having its top edge extending flush with the upper termination of said reduced end, the upper end of said second-named collar being enlarged and threaded and the lower end thereof being rigidly attached to said bowl.

In testimony whereof I affix my signature in presence of two witnesses.

EDWARD L. GAYLORD.
